DESIGN FOR A LIFE RAFT

Walter E. B. Harkins, Brooklyn, N. Y.

Application March 9, 1944, Serial No. 112,832

Term of patent 14 years

(Cl. D71—1)

To all whom it may concern:

Be it known that I, Walter E. B. Harkins, a citizen of the United States of America, residing in the Borough of Brooklyn, county of Kings, and State of New York, have invented a new, original, and ornamental Design for a Life Raft, of which the following is a specification, reference being had to the accompanying drawing, forming part thereof.

Fig. 1 is a perspective view of a life raft showing my new design.

Fig. 2 is a perspective view illustrating the life raft in closed position.

The dominant feature of my design resides in the portions shown in solid lines.

I claim:

The ornamental design for a life raft, substantially as shown and described.

WALTER E. B. HARKINS.
